UNITED STATES PATENT OFFICE.

JOHN H. PITEZEL, OF THREE RIVERS, MICHIGAN.

IMPROVED SEWING-CLAMPS.

Specification forming part of Letters Patent No. **59,448**, dated November 6, 1866.

To all whom it may concern:

Be it known that I, JOHN H. PITEZEL, of Three Rivers, in the county of St. Joseph and State of Michigan, have invented a new and useful Improvement in Sewing-Clamps for Stitching Leather and other Materials, of which the following is a full, clear, and exact description, reference being had to the accompanying drawings, which make part of this specification, and in which—

Figure 1 represents a view, in perspective, of my improved stitching-clamp; and Fig. 2, a vertical transverse section through the jaws of the same.

It is the object of my invention to produce a cheap, simple, and efficient clamp which can readily be attached to any bench, table, or stand; and to these ends the improvement herein claimed consists in combining, with a detachable stand, a clamp composed of a short fixed leg or jaw and a long movable leg or jaw, operated by a strap and treadle, to clamp the article to be held, with a spring interposed between the legs to open them when the pressure is released.

In the accompanying drawings my improved clamp is shown as applied to a stitching-horse, such as ordinarily used by saddlers and harness-makers.

A base or bed plate, A A', of cast-iron, is formed with two branches or arms—one, A, passing above, the other, A', below, the stool or table, to give a firm support. A ledge, flange, or socket, B, is formed upon the base A, with a central rib, b, upon it. A curved clamp or leg, C, of wood, is mortised to fit this socket and rib, and is firmly held by a screw-bolt, c, passing through the leg and rib.

A similar jaw or leg, D, is, in like manner, secured to a socket, E, pivoted to play vertically in planes parallel to the fixed clamp C. This socket plays on a fulcrum, e, in the base A, and passes down through a slot in it, terminating in a leg, F, to which one end of a strap, G, is attached. This strap passes over a pul-

ley, H, mounted on a leg, I, projecting below the bed-plate, and is attached to a treadle, J, one end of which is pivoted to a cross-bar, K, while the other is free to play up or down, but can be held in any desired position by a ratchet, L, on the frame. The jaws are closed by pressing on the treadle. To open them automatically I interpose a rubber spring, M, between the fixed and movable jaws.

The bed-plate is firmly secured to the table by a through-bolt, N, and by screws n.

In operation, the article to be stitched is to be placed within the jaws C D, and clamped by pressing with the foot upon the treadle, which is held by catching in the ratchet. To release the clamp the treadle is detached from the rack, when the spring instantly opens the jaws and releases the work.

My invention is applicable to the use of saddlers, harness-makers, coach-trimmers, trunk-makers, and others.

I have shown my clamp as applied to a saddler's stool; but it is equally adaptable to a work-bench or table.

What I claim as my invention, and desire to secure by Letters Patent, is—

1. The bed-plate A A', constructed as described.

2. The combination of the cast-iron bed-plate and legs with the wooden clamping-jaws, constructed and operating substantially as described.

3. The combination, with the bed-plate, of the short fixed jaw and the long movable jaw, the strap-connection, and the treadle, arranged and operating as described.

4. The combination of the fixed and movable jaws with the interposed rubber spring, arranged and operating as described.

In testimony whereof I have hereunto subscribed my name.

JNO. H. PITEZEL.
